(57) **CLAIM**

The ornamental design for a quick mounting device, as shown and described.

DESCRIPTION

This present application is related to U.S. patent application Ser. No. 13/541,735 filed in the name of the inventor of the present application on the same date herewith, which is incorporated herein by reference.

FIG. 1 is a front perspective view of a quick mounting device, showing my new design;

FIG. 2 is a top elevational view thereof;

FIG. 3 is a side elevational view thereof; and,

FIG. 4 is an end elevational view thereof.

The broken lines showing the joints, chamfers, fastener joins and the clamp fenders in FIGS. 1, 3 and 4 are for environmental purposes only and form no part of the claimed design.
